[57] CLAIM

The ornamental design for a vehicular handset telephone control unit or similar article, as shown and described.

DESCRIPTION

FIG. 1 is a left side, top and front perspective view of a vehicular handset telephone control unit or similar article showing our new design;

FIG. 2 is a right side elevational view thereof;

FIG. 3 is a rear elevational view thereof; and

FIG. 4 is a bottom plan view thereof.

The broken line showing of sundry areas in FIG. 1 on the left side, top and front, including pushbuttons; and ear piece and display panel in FIG. 3 is for illustrative purposes only and forms no part of the claimed design.
